ENLARGING THE DIAMETER OF HOLLOW METAL ARTICLES

Fritz Singer, Nuremberg, Germany, assignor to
Tubus A. G., Glarus, SwitzerlandApplication January 28, 1936, Serial No. 61,152
In Germany May 14, 1934

4 Claims. (Cl. 205—4)

This invention relates to the enlarging of the diameter of hollow metal articles while avoiding more than a moderate reduction of the wall thickness.

5 It is among the objects of the invention to provide a method of enlarging the diameter, i. e. expanding, of hollow metallic articles, such as tubes, which effectively expands the tubes without great change in wall thickness, is simple, effective and 10 readily practiced, and whose practice requires only simple, compact and relatively inexpensive apparatus.

A further object is to provide apparatus for performing the method.

15 The invention will be described with reference to the accompanying drawings in which Fig. 1 is a longitudinal sectional view through the preferred embodiment of apparatus adapted for the practice of the method; and Fig. 2 a plan view, partly in section, of the apparatus shown in Fig. 1.

20 Figure 3 is a longitudinal sectional view, partly broken away, diagrammatically showing a smoothing die over the emerging extremity of the enlarged tube.

25 In accordance with the invention the article, such as a tube, is expanded by advancing a relatively short length over a tapered mandrel whose diameter is greater than that of the tube and is productive of the desired enlarged diameter. Successive portions of the tube are then advanced stepwise over the mandrel. The portions advanced over the mandrel expand freely, i. e., they do not move between the mandrel and a die to cause reduction of wall thickness but rather are expanded freely. Thereby the article is expanded progressively and with only slight or moderate reduction in wall thickness to enlarge the diameter along its entire length, or along a desired portion thereof.

30 Because the invention is especially adapted to the treatment of tubes it will be described further with reference thereto by way of illustration. Suitably the tube is mounted on a mandrel rod the rear end of which is removably mounted in the machine frame and the free front end of which is provided with a tapered expanding mandrel head the diameter of which is greater than the inner diameter of the tube to be enlarged.

35 The advancing of the tubular article is effected by means of any suitable feeding or tube-gripping mechanism mounted on a machine part for reciprocation in the direction of the axis of the supporting, or mandrel, rod. Reciprocation of the gripping mechanism carrier is performed by

any suitable means, for instance a crank. The gripping mechanism may be of any automatic kind or controlled by suitable means in such a manner that at the beginning of the forward stroke of the gripping mechanism carrier the 5 tubular article is gripped while it is released when said carrier returns to its initial position. In this manner the tube is gripped and moved forwardly to advance a relatively short length over the mandrel head. The gripping mechanism then releases the tube and is retracted; it then grips the tube and is again advanced to move another portion of the tube onto the mandrel head.

40 Thus the method provided by the present invention differs from certain known processes in 15 that the mandrel is not reciprocated but is mounted fast, and in that the tube expands freely. The enlarging of the tube is effected exclusively by periodically advancing the tube on its axially fixed supporting rod towards the fixed mandrel head. 20 Accordingly in the present method only the gripping mechanism carrier has to be reciprocated, thus effecting simultaneously feeding of the tube and enlarging of its diameter. A further feature 25 of the present invention which constitutes an advance over older methods consists in that tubes of great lengths and small wall thicknesses can be worked in the hot or cold states while with the prior processes only hot thick-walled tubes of 30 small lengths could be successfully treated due to the bending strains exerted on the mandrel. For enlarging thick-walled short tubular articles there is in practice no need as such tubes can be produced directly by known rolling and pressing processes in a more economical manner and 35 in great lengths.

45 As the apparatus necessary for performing the process according to the invention is of very simple construction and requires only very small investment cost, the invention may advantageously be used for extending the range of tube sizes to be produced by means of existing tube-producing equipment. Furthermore it can be utilized for smoothing the inner surface of roughly rolled or pressed tubes, and it is adapted 45 for completely or partially enlarging tubular articles.

50 By my new process I can, for instance, satisfactorily convert brass or steel tube having an outer diameter of 0.945 inch into a tube having 50 an outer diameter of 1.1 inch with a reduction of wall thickness of only about 8 per cent.

55 Although the tube expands freely on the mandrel head, it may in some instances be advantageous to use a die ring, not for the purpose of 55

obtaining any substantial reduction of the wall thickness but in order to smooth the outer surface of the tube whereby tubes can be produced of absolutely smooth and cold-hardened inner 5 and outer surfaces. Such a ring as used in the practice of this invention is shown at K in Figure 3 and does not effect any great reduction in wall thickness.

Although various forms of apparatus may be 10 used for practicing the method as thus described, I now prefer to use an apparatus designed purely for enlarging because it can be of simple and inexpensive design. Having reference to the accompanying drawings, which show the preferred 15 embodiment, a tube 1 is slidably supported on a mandrel rod 2 which is provided at its forward end with a cylindrical mandrel head 3 having a diameter greater than the inside diameter of the tube and adapted to produce a desired increase 20 in tube diameter. A tapered, or conical, portion 4 connects the cylindrical surface 5 of the mandrel head and the cylindrical surface of the rod. At its rear end rod 2 is removably supported by a rod carrier 6 mounted on a rearwardly 25 extending arm 7 of the machine frame 8 by means of screws 9, arm 7 being secured to the machine frame by means of screws 10.

To permit the end of supporting rod 1 to be cleared in order to receive a tube 1 it is provided 30 with a reduced portion 11 which engages recesses 12 and 13 in the upper end of rod carrier 6 and a cover-plate 14 which by means of screws 15 is secured to rod carrier 6.

A crank shaft 16 is journaled in the side walls 35 of machine frame 8. The crank pin 17 of the crank shaft is connected to one end of a push rod 18 the other end of which is journaled in a slide block 19 slidably disposed in a slot 20 provided in a downwardly extending arm 21 of a carrier 22 for the feeding mechanism. Secured 40 to the slide block 19 is a stud 23 which coacts together with the downwardly bent arm 24a of a flat-faced lever 24 journaled on a pin 26 carried by lugs 25 of the front part of the feeding 45 mechanism carrier arm 21. The upwardly extending arm 24b of lever 24 is bifurcated to provide for free passage of the tube and the supporting rod therethrough. The bifurcated ends of the upwardly extending arm 24b of lever 24 50 form an abutment for a coil spring 27 encircling the tube between said arm 24b and the clamping jaws 28 of the feeding mechanism.

The feeding mechanism is mounted between side walls 29 on the feeding mechanism carrier 55 21 and consists of the outer supporting blocks 30 secured by screws 31 to the side walls 29, wedge pieces 32, rollers 33, the clamping jaws 28 and the chuck 34. Springs 35 constantly urge the rollers to the left, thus releasing the clamping jaws and the chuck. The side walls 29, 29 are prevented from spreading by any convenient means not shown, such, for example, as forming the two side walls in a single piece or encircling them with a hood or bonnet comprising a cover 65 plate 36 and integral downwardly depending flanges.

The operation of the apparatus is as follows: In the position of the crank as shown in Fig. 1 slide block 19, and consequently stud 23, are in 70 their right-end position. As there is no pressure on the spring coil 27, the chuck 34 is released through the action of springs 35 on rollers 33, thus permitting free passage of the tube while the latter is slipped on supporting rod 2 so as to 75 engage the tapered end of the mandrel 5. After

securing the rear end of the supporting rod 2 on the rod carrier 6, the crank drive is set into motion. During the first part of the crank stroke the slide block 19 and the stud 23 are advanced to the left. When the stud 23 contacts arm 24a 5 of the lever 24 the latter is caused to move in a clockwise direction so as to compress spring 27 thereby forcing the clamping jaws 28 to move to the right causing rotation of the rollers 33 and thereby the clamping jaws 28 are pressed towards the chuck 34 thus gripping the tube.

As soon as the front face of slide block 19 contacts arm 21 the feeding mechanism carrier 22 together with the lever 24 are moved to the left thereby advancing tube 1 on the supporting rod 15 2 towards the mandrel 5 and enlarging a relatively short portion of the tube. During the first part of the return stroke of the crank only the slide block 19 is returned within the recess 20, which results in the stud 23 releasing arm 24a 20 of lever 24, the pressure on spring coil 27 is released, and the tube is likewise released by the jaws. As soon as the back face of slide block 19 contacts arm 21, the feeding mechanism carrier is returned to its initial position. The tube 25 being released from the frictional grip of the chuck the feeding mechanism is allowed to slide over the tube held fast by the frictional grip of the tube on the mandrel 5. On the next rotation of the crank the cycle is repeated, thus enlarging 30 the diameter of the next succeeding portion of the tube, and this is repeated until the tube, or a desired portion, has been enlarged.

According to the provisions of the patent statutes, I have explained the principle and mode of 35 operation of my invention, and have illustrated and described what I now consider to be its best embodiment. However, I desire to have it understood that, within the scope of the appended claims, the invention may be practiced otherwise 40 than as specifically illustrated and described.

I claim:

1. That method of expanding hollow metallic articles, such as tubes, which comprises gripping and advancing a relatively short length of the 45 article freely over a tapered mandrel head having a diameter greater than that of the article, and repeating such advancement step-by-step to expand continuously successive relatively short lengths, and thereby freely expanding the diameter of the article with relatively low change in 50 wall thickness, the said gripping taking place a relatively short distance from the mandrel head.

2. That method of expanding hollow metallic articles, such as tubes, which comprises mounting 55 the article on a mandrel removably mounted at its rear end and provided at its forward end with a tapered expanding head having a diameter greater than that of the article, gripping the article and forcing a relatively short length over 60 said head to freely expand said length thereover, and repeating such advancement step-by-step to expand continuously successive relatively short lengths, and thereby freely expanding the diameter of the article with relatively low change in 65 wall thickness, the said gripping taking place a relatively short distance from the mandrel head.

3. Apparatus for enlarging the diameter of tubular metallic articles comprising a frame, a mandrel rod having its rear end removably 70 mounted in said frame and provided at its forward end with a tapered expanding head, said expanding head being free of encircling tube-compressing means, and means for successively advancing relatively short lengths of a tube along 75

said mandrel rod and over said head to freely expand the tube with relatively low changes in wall thickness, said means comprising a carrier, means for reciprocating the carrier axially of said mandrel rod, jaws mounted in said carrier for movement axially and laterally of said rod, a block rigidly mounted in said carrier adjacent each of said jaws, means operated by said reciprocating means during the first part of its forward stroke for moving said jaws rearwardly of said blocks, means associated with each block for

moving the adjacent jaw laterally into gripping engagement with said tube when said jaw is moved rearwardly of said block, and means for moving said jaws forwardly of said blocks when said reciprocating means starts its back stroke, 5 whereby to release the jaws from the tube.

4. A method according to claim 1 in which said expanded portions are die-smoothed without substantial change in wall thickness of the expanded portion. 10
